MAURICE P. SULLIVAN, OF NEW YORK, N. Y.

SPARK-PLUG.

1,275,102.

Specification of Letters Patent. Patented Aug. 6, 1918.

Application filed October 5, 1916. Serial No. 123,843.

To all whom it may concern:

Be it known that I, MAURICE P. SULLIVAN, a citizen of the United States, residing at New York, in the county and State of New 5 York, have invented certain new and useful Improvements in Spark-Plugs, of which the following is a specification.

My invention relates to sparking means used in connection with internal combustion engines, and in particular it has to do with that class in which electric sparks are employed to ignite the explosive mixtures in the engine cylinders.

Owing to the severe working conditions 15 which spark plugs are called upon to withstand, such as the intense heat and pressure of the exploding gases, the destructive action of oils and combustion products, and the wearing action of the electric sparks, it is the case that ordinary plugs of the present day 20 practice cannot be relied upon to give satisfactory service for any great length of time. This fact is especially evident when it is taken into consideration that the electrical 25 requirements are such as to dictate the use of a certain class of materials for insulation purposes, all of which materials are mechanically, by far inferior and less durable than the other parts of the plug. The 30 inevitable result is that after a time the weaker portions are liable to become impaired or damaged, thereby rendering the whole device ineffective.

It is one of the main objects of my invention 35 to construct a plug in which the liability of damage is comparatively small, and at the same time to provide means for replacing the less durable parts of the plug as they become worn or broken. By this 40 provision an old plug may be easily and quickly rendered substantially as good as new, and at a relatively low cost.

Another object is to construct the central 45 electrode assembly so that the terminal thereof may be removed and a new one substituted in its place without removing the shell portion from its working position in the engine cylinder.

It is also another object to provide a plug 50 in which the ground terminal is so arranged that the same may be renewed without the necessity of detaching the shell from the engine.

With these and other objects in view my 55 invention further contemplates certain novel features of construction and operation, all

of which are hereinafter described and particularly pointed out in the appended claims.

In the accompanying drawing Figure 1 is a view, partly in section, showing a spark 60 plug in which the features of my invention are embodied.

Fig. 2 is a view, partly in section, and on an enlarged scale, illustrating the replaceable portion of the plug.

Fig. 3 is a view similar in nature to Fig. 1, yet showing a modified form of construction.

With particular reference to the drawing, wherein like characters designate like parts in the respective views, 1 is the shell or body member of the plug having an external thread 2 and shoulder 3, a suitable gasket usually being used below shoulder 3, which permit said plug to be applied to the cylinder of an engine with the assurance of a tight joint. A gland 4 carries a screw thread 5 adapted to engage an internal thread in the upper portion of the shell 1. Extending through a centrally disposed bore 80 in gland 4 is the upper portion of the central electrode 6, this electrode has a thread 7 turned on its upper end while at its lower end, as at 6, it is of somewhat larger diameter. Said upper portion of the central electrode 85 may be of any suitable conducting material and carries a core 8 of insulation, such as mica or the like. The core 8 is wrapped firmly about the electrode 6 and is of such diameter as to provide a press-fit 90 when assembled in position within the gland 4. An insulating jacket 9 of porcelain or other suitable material fits on over the screw thread 7 and is held in place by a threaded cap 10. In the lower end of electrode 6 95 there is a concentric recess 11 the purpose of which is hereinafter explained.

The shell 1 is of hollow formation having, as hereinbefore stated, an internal thread at its upper end. The lower end of the shell 100 is provided with a smooth circular bore of a diameter somewhat less than that of said threaded portion. At the junction of said threaded and smooth portions of the bore of shell 1 there is formed a beveled annular 105 shoulder 12. Coöoperating with the upper portion of the central electrode 6 is a supplemental or lower portion 13 in the form of a spindle, having at one end a circular disk 14 and an enlarged projecting point 15, 110 said disk 14 and projecting point 15 being, if desirable, constructed integral with the

spindle 13. This supplemental member 13 together with the member 6 serves to form the complete central electrode of the plug, and since said supplemental member provides one of the sparking points, it may be of any suitable material to meet the conditions imposed upon the terminal points of spark plug electrodes.

Referring now to Fig. 2, in which the essential features of my invention are embodied, 16 is a cylindrical shell or cartridge having at its upper end a beveled flange 17. Within this cartridge and engaging the same with a tight fit is a core of insulating material 18, preferably of porcelain, of hollow construction, and having a shoulder 19 intermediate of its ends provided with a central hole of a diameter sufficient to accommodate the spindle 13 with a snug fit, yet permitting the same to be removed if desirable. When thus assembled the disk 14 seats against shoulder 19 holding spindle 13 in proper position. In the bottom of core 18 is an annular groove adapted to accommodate the annular ring 20. Ring 20, which is of suitable material, carries the ground electrode terminal 21, and is held in place by a flange 22 of the cartridge 16.

The construction shown in Fig. 2 is a unitary structure in itself and is replaceable with respect to the plug proper. When assembled, the cartridge 16 of said unitary structure slides into the previously mentioned bore in shell 1, the shoulder 17 engaging the beveled shoulder 12 of said shell. The gland 4 also has a beveled shoulder 23 which, when said gland is adjusted in position, engages shoulder 17, presses the same firmly against shoulder 12 and thereby insures a tight joint. As the gland 4 is screwed in place the concentric recess 11 in the bottom of electrode 6 passes on over and around the projecting point 15. A slight gap is retained between the bottom of the recess and the end of said point in order that shoulders 23, 17 and 12 may seat against one another properly. The spacing between the side walls of recess 11 and the point 15 is however, so slight that the current in traversing the central electrode readily passes from member 6 to point 15 and thence to the spark gap.

In the modification as shown in Fig. 3 I have made the recess 11 in the end of member 6 somewhat deeper, and provided the same with an internal screw-thread. The point 15 also carries a thread which engages said internal thread to hold the disk 14 firmly up against the end of member 6. When the plug shown in this figure is completely assembled there is a small spacing left between disk 14 and the shoulder 19 of the insulating core 18 in order not to interfere with a proper engagement between shoulders 23, 17 and 12.

According to my invention I have provided a construction in which the less durable parts of the plug, such as the insulating core 18, ground electrode terminal 21, and central electrode terminal 13 are all brought together in a simple compact unitary structure, and which may be readily detached as a unitary structure from the remainder of the plug without removing the shell 1 from its position in the engine cylinder for the purpose of inspection or the substitution of new parts, and when said new unitary structure is installed in the old shell the advantage of a new gasket engaging surface is thereby obtained. A plug embodying these features of construction makes inspection and replacement of parts a very simple matter, since it is not necessary to disturb the shell or body member. This is accomplished as hereinbefore described by giving to the hollow shell 1 an internal diameter at its upper end sufficient to allow the cartridge 16 and its associated parts to be inserted within or extracted from its working position in said shell 1. In practice this shell, owing to moisture and other conditions, is liable to become rusted into the engine cylinder with the result that considerable difficulty is experienced in removing the same, which removal is often necessary for inspection and repair where the ordinary construction is used. In case the central electrode terminal alone becomes worn or damaged it may be replaced by a new one without necessitating the change of any other parts of the plug.

Another characteristic of the replaceable unitary structure is the manner in which the porcelain core 18 is inclosed by the metal cartridge 16. In ordinary porcelain plugs the porcelain insulation is openly exposed on all sides to the heat and concussion of the engine gases, and owing to the brittle nature of this material serious trouble is often encountered. In my construction the cartridge 16 serves as a protecting housing which aids materially in relieving the porcelain insulator from these dangerous pressure conditions.

Obviously many changes and alterations may be made in the construction shown and I do not care to limit myself to the exact details shown therein.

Having thus described my invention what I claim is:

1. In an electrical spark plug, a body member adapted to be attached to the cylinder of a gas engine or the like, a gland adapted to be screwed into said body member and having an insulating part press-fitted thereon, said insulating part carrying a portion of a central electrode; and a unitary structure including a metallic cartridge, a ground electrode terminal, an insulating core and a supplemental portion of

said central electrode including the terminal thereof being supported by said core and detachable therefrom without removing said body from the engine cylinder.

5. 2. In an electrical spark plug, a body member adapted to be attached to the cylinder of a gas engine or the like; a gland supported by said body member; a portion of a central electrode arranged within and insulated from said gland; and a unitary structure including a metallic cartridge, a ground electrode terminal, an insulating core, and a supplemental portion of said central electrode including the terminal thereof being supported by said core and detachable therefrom without removing said body from the engine cylinder.

3. In an electrical spark plug, a hollow shell adapted to be attached to the cylinder of a gas engine or the like, said hollow shell having an enlarged internal diameter at its upper end with threads thereon, a unitary structure including; a metallic cartridge having its upper end flared to fit within said enlarged diameter and a ground electrode attached to the other end thereof, an insulating core within said cartridge, a central electrode terminal carried by said core adapted to coöperate with the said ground electrode; a second insulator carrying a portion of a central electrode, a gland adapted to be press-fitted onto said second electrode and having threads to engage threads on the enlarged part of said shell and to further engage the flared portion of said cartridge to hold the same securely in place within the shell and provide a gas-tight joint, with means for connecting said central electrode portions in operative relationship.

4. In an electrical spark plug the combination of a body member, a gland supported thereby, central and ground electrodes, said central electrode consisting of an upper and a lower portion the upper portion having a recess in its end and being secured within said gland but insulated therefrom, the lower portion of said central electrode having a disk near one end and a projecting point thereabove, a metallic cartridge having a flange at one end, a hollow insulating member contained within said cartridge, a bridging portion within the insulating member having an aperture therein adapted to receive the lower portion of the central electrode, said metallic cartridge being so arranged within the body member that the projecting point on the lower portion of the central electrode is inclosed by said recess,

the disk thereon serving as a guide to hold 60 the same in position, and means carried by the gland and body member to coöperate with the flange on said cartridge for the purpose of providing a tight joint.

5. In an electrical spark plug the combination of a body member of hollow formation with a beveled shoulder intermediate of its ends, a gland supported by the body member and having a beveled shoulder at one end thereof; a portion of a central electrode with a recess in the end thereof; said portion being supported by and insulated from said gland; a unitary structure comprising a metallic cartridge having a flange at one end, a hollow insulating core supported within said cartridge and having an internal shoulder, a supplemental portion of said central electrode provided with a projecting point at its upper end and being detachably supported within said insulating 70 core by said internal shoulder, and the terminal of a ground electrode; said unitary structure being detachably arranged within the body member in such a way that the flange of said cartridge coöperates with the 75 beveled shoulders of the gland and body member to provide a tight joint; said projecting point of the supplemental portion being adapted to coöperate with said recess to complete the central electrode. 90

6. In an electrical spark plug the combination of a body member having an internal beveled shoulder, a gland having a beveled shoulder and supported by said body member, a central electrode comprising two 95 parts one of which has a recess in its lower end and is arranged within said gland but insulated therefrom, a cartridge having a flange at one end, a hollow insulating member secured within said cartridge with an 100 internal shoulder thereon, the second part of said central electrode being supported by said internal shoulder and having an enlarged projecting point which coöperates with the recess in the first said part of the 105 central electrode in such a way that the flange on said cartridge and the beveled shoulders of the gland and body member are permitted to form a tight joint when the plug is assembled, a ground electrode terminal, said cartridge, insulating member, ground electrode, and the second part of said central electrode comprising a single 110 unitary structure which is detachably supported within the body member of the plug. 115

In witness whereof I affix my signature.

MAURICE P. SULLIVAN.
